(57) **CLAIM**

The ornamental design for a cigar-cutter ashtray, as shown and described.

DESCRIPTION

FIG. 1 is a perspective view of a cigar-cutter ashtray showing my new design in a closed position;

FIG. 2 is a perspective view of the cigar-cutter ashtray showing my new design in an open position;

FIG. 3 is a top plan view thereof;

FIG. 4 is a bottom plan view thereof;

FIG. 5 is a front elevational view thereof, the rear elevational view being a mirror image thereof;

FIG. 6 is a side elevational view thereof, the opposite side being identical thereto;

FIG. 7 is an exploded perspective view thereof showing a removable tray, guillotine cutter and punch cutter; and,

FIG. 8 is a perspective view thereof showing the cover and cutter in open positions with a cigar resting in the cigar rest. The portions shown in broken lines are included for illustrative purpose only and form no part of the claimed design.
